(57) **CLAIM**

The ornamental design for footwear, as shown and described.

DESCRIPTION

FIG. 1 is a front-top perspective view of the footwear, showing the new design;

FIG. 2 is a bottom perspective view of the footwear of FIG. 1;

FIG. 3 is a lateral side view of the footwear of FIG. 1;

FIG. 4 is a medial side view of the footwear of FIG. 1;

FIG. 5 is a front view of the footwear of FIG. 1;

FIG. 6 is a rear view of the footwear of FIG. 1;

FIG. 7 is a top plan view of the footwear of FIG. 1; and,

FIG. 8 is a bottom plan view of the footwear of FIG. 1.

The drawings show the design of footwear suitable for being worn on a right foot. The ornamental design also includes the mirror images of drawings, i.e., the design of footwear suitable for being worn on the left foot. The broken lines in the drawing views form no part of the claimed design.
